FIG. 5

FIG. 6

FIG. 7

FIG. 8

FIG. 1 is a perspective view of the tape recorder embodying our new design with the cover thereof in closed position as viewed from the front and left side thereof;

FIG. 2 is a perspective view of the tape recorder with the cover thereof in open position;

FIG. 3 is a top plan view of the tape recorder with the cover thereof in open position;

FIG. 4 is a front elevational view of the tape recorder depicted in FIG. 1;

FIGS. 5 and 6 are side elevational views when viewed from the left and right ends respectively of the tape recorder as depicted in FIGS. 3 and 4;

FIG. 7 is a rear elevational view of the tape recorder shown in FIGS. 3 and 4;

FIG. 8 is a bottom plan view of the tape recorder with the cover in open position.

We claim:

The ornamental design for a tape recorder, as shown.
